J. L. GOODWIN.
BULL GEAR DUST SHIELD FOR TRACTORS.
APPLICATION FILED SEPT. 15, 1920.

1,884,189.

Patented July 12, 1921.

INVENTOR.

UNITED STATES PATENT OFFICE.

JAY L. GOODWIN, OF STOCKTON, CALIFORNIA, ASSIGNOR OF ONE-HALF TO WILLIAM THOMAS, OF STOCKTON, CALIFORNIA.

BULL-GEAR DUST-SHIELD FOR TRACTORS.

1,384,189.

Specification of Letters Patent. Patented July 12, 1921.

Application filed September 15, 1920. Serial No. 410,355.

To all whom it may concern:

Be it known that I, JAY L. GOODWIN, a citizen of the United States, residing at Stockton, in the county of San Joaquin, State of California, have invented certain new and useful Improvements in Bull-Gear Dust-Shields for Tractors; and I do declare the following to be a full, clear, and exact description of the same, reference being had 10 to the accompanying drawings, and to the characters of reference marked thereon, which form a part of this application.

This invention relates to improvements in keeping dust and dirt out of the bull gears 15 of tractors employing this type of drive, being especially designed and shown to be used on tractors of the "Moline" type.

A dust shield of a sort is provided on these machines, but it performs somewhat inadequately, since while it serves to keep dust and dirt from being blown or carried directly onto the face of the gear teeth, a space is left between the outside of the gear and shield of ample size to readily allow 25 dust and dirt to pass therebetween, which will occur when the machine is in operation, especially in dry ground, when a cloud of dust is constantly hovering around the wheels and naturally sifts sooner or later, 30 even through small apertures.

The principal object of my invention is to eliminate this objectionable feature by providing an absolutely tight shield for the gear in connection with the shield already 35 provided, and without necessitating alterations of any kind being made on the standard equipment of the tractor.

Another object is to provide a device for the purpose which may be installed or removed without dismantling the tractor.

I have also provided two forms of the device, one of which is particularly adapted to be used when a dry contact is desired, and the other in connection with lubricating 45 means.

A further object of the invention is to produce a simple and inexpensive device and yet one which will be exceedingly effective for the purposes which it is designed.

These objects I accomplish by means of such structure and relative arrangement of parts as will fully appear by a perusal of the following specification and claims.

In the drawings similar characters of

reference indicate the corresponding parts 55 in the several views.

Figure 1 is a side elevation of a tractor bull-gear, detached, showing one form of my improved dust shield installed in connection therewith.

Fig. 2 is an enlarged cross section taken on a line 2—2 of Fig. 1.

Fig. 3 is a similar view taken on a line 3—3 of Fig. 1.

Fig. 4 is a fragmentary cross section of a 65 bull gear showing a modified form of shield.

Referring now more particularly to the characters of reference on the drawings, the numeral 1 denotes the bull gear, the outer side of which is solid throughout its entire 70 area as at 2, the gear being fixed to its driving wheel by means of integral and radially positioned lugs 3.

The inner side of the bull gear, which in this case is of the internal type, is of course 75 open throughout to receive the driving pinion (not shown). A dust shield or hood is provided with the gear as standard equipment, consisting of a plate 4 spaced somewhat from the inner face of the gear, and 80 a flange 5 extending partly over the periphery of the gear and concentric therewith, and also spaced somewhat therefrom.

It is on account of this latter spacing that this shield is inadequate for its purpose, and 85 it is this defect that I propose to remedy with my attachment.

This consists of a hood comprising a ring 6 concentric with the gear and positioned beyond the shield-flange 5, the gear being 90 stepped down or shouldered at this point as at 7, the flange being spaced sufficiently therefrom to allow a flat strip or gasket of felt 8 or some similar material being placed between the flange and gear-shoulder, and 95 held by lips 9 placed at intervals on the outer edge of the flange.

An extension 10 from the flange 6 projects over the shield 5 and concentric therewith, and is provided with a channel 11, 100 whose opening faces the axis of the gear.

This channel is adapted to receive and hold a felt ring 12, which bears against the shield 5 sufficiently to prevent the passage of dust therewith.

In order to readily mount my shield or hood, the same is preferably made in four sections, corresponding to the number of

lugs 3 on the gear, each section being provided with end lips 13 arranged to align with the lugs 3 and to be secured thereto with the same bolts 14 which hold said gear to the wheel, the felt members 8 and 12 being likewise made in sections, though for simplicity of language they have been spoken of as single members. This form is especially intended for a dry rubbing contact.

10 In the lubricated form of the device shown in Fig. 4, I provide a double channeled ring 15 having outer and inner concentric channels 16 and 17, the inner channel 16 opening onto the shield 5 and having 15 therein a felt strip or gasket 18 bearing on the shield 5, and the outer channel 17 having a felt ring 19 projecting therebeyond.

The member 15 is provided with opposed flanges 20 which bear on the shield 5, the 20 purpose of the gasket 18 being to make a dust-tight fit between the channel member and the shield 5.

The member 15 is preferably made in two equal sized sections, each one-half a circle, 25 the abutting ends being provided with radial flanges 21 adapted to be clamped together by bolts 22.

The member 19 projects into a channel 23 formed by the inner flange 24 of a hood 25 30 concentric with the shield 5, and by a flange 26 parallel to the flange 24 but adjustable relative thereto.

The member 19 does not fill this channel, but leaves a peripheral space therebeyond 35 for the reception of a lubricating substance. The flange 26 however is moved to bear against the felt with a pressure sufficient to preclude the escape of the lubricant therepast. The hood 25 beyond the channel 40 bends toward the gear as at 27 to join the ring or flange 6^a which holds a gasket 8^a in the same manner as the ring 6, it being of course understood that the hood and portion 27 form a solid surface throughout their 45 extent, and that they are also made in sections mounted to the bull-gear in the same manner as the first described form.

It will be noted that while in the first described form the main felt ring 12 moves 50 with the bull-gear and bears dry against the stationary shield 5, in the latter described type the main felt ring 19 is stationary, while the lubricant-filled channel formed with the hood revolves thereabout.

55 In the latter type, the abutting ends of the outer channel are covered by overlapping and removably secured plates or strips (not shown), preferably having a lining of felt, so as to prevent the escape of the lubricant 60 between such ends.

From the foregoing description it will be readily seen that I have produced such a device as substantially fulfills the objects of the invention as set forth herein.

65 While this specification sets forth in de-

tail the present and preferred construction of the device, still in practice such deviations from such detail may be resorted to as do not form a departure from the spirit of the invention, as defined by the appended 70 claims.

Having thus described my invention, what I claim as new and useful and desire to secure by Letters Patent is:—

1. A dust shield for tractor bull-gears 75 comprising in combination with a stationary hood projecting partly over the gear and spaced from the outer periphery thereof, a hood overlapping the first named hood and spaced therefrom, such hood comprising a 80 plurality of sections to form a complete circumference and fixed to the gear beyond the first named hood, and a packing ring between the inner and outer hoods at their overlapping portions, such ring being made 85 in sections to correspond to the sections of the outer hood.

2. A dust shield for tractor-bull gears comprising in combination with a stationary hood projecting partly over the gear and 90 spaced from the outer periphery thereof, a hood overlapping the first named hood and spaced therefrom, such hood comprising a plurality of sections to form a complete circumference and fixed to the gear beyond the 95 first named hood, and a packing ring fixed to each section and bearing on the outer face of the inner hood.

3. A dust shield for tractor-bull gears comprising in combination with a stationary 100 hood projecting partly over the gear and spaced from the outer periphery thereof, a hood overlapping the first named hood and spaced therefrom, such hood comprising a plurality of sections to form a complete circumference and fixed to the gear beyond the 105 first named hood, a packing gasket between the outer hood and the gear, and a packing ring between the overlapping portions of the inner and outer hoods. 110

4. A dust shield for tractor-bull gears comprising in combination with a stationary hood projecting partly over the gear and spaced from the outer periphery thereof, a 115 hood fixed to the gear beyond the first named hood, and projecting thereover, a channel formed with the outer hood concentric with the inner hood and open theretoward, and a packing ring clamped about the inner hood and projecting into the channel, and spaced 120 from the outer face thereof, whereby a lubricant may be introduced therebetween.

5. A dust shield for tractor-bull gears comprising in combination with a stationary hood projecting partly over the gear and 125 spaced from the outer periphery thereof, a hood fixed to the gear beyond the first named hood and projecting thereover, a channel formed with the outer hood concentric with the inner hood and open theretoward, and 130

a packing ring clamped about the inner hood and projecting into the channel, one of the sides of said channel being adjustable whereby the frictional contact of the ring therewith may be varied.

6. A dust shield for tractor-bull gears comprising in combination with a stationary hood projecting partly over the gear and spaced from the outer periphery thereof, a hood fixed to the gear beyond the first named hood and projecting thereover, a channel formed with the outer hood concentric with the inner hood and open toward, a double-channeled member formed

of sections to make a complete circumference and adapted to be clamped about the inner hood, one of the channels of said member opening toward the inner hood and the other toward the outer hood, a gasket in the inner channel bearing on the adjacent hood, and a packing ring fixed in the outer channel and projecting into the channel in the outer hood, and spaced from the outer face thereof, such channels being in alignment.

In testimony whereof I affix my signature.

JAY L. GOODWIN.
